F. S. YODER,
DENTAL CHIP BLOWER,
APPLICATION FILED AUG. 3, 1915.

1,166,033.

Patented Dec. 28, 1915.

UNITED STATES PATENT OFFICE.

FREDERICK S. YODER, OF WERNERSVILLE, PENNSYLVANIA.

DENTAL CHIP-BLOWER.

1,166,038.

Specification of Letters Patent. Patented Dec. 28, 1915.

Application filed August 3, 1915. Serial No. 43,427.

To all whom it may concern:

Be it known that I, FREDERICK S. YODER, a citizen of the United States, residing at Wernersville, in the county of Berks and 5 State of Pennsylvania, have invented certain new and useful Improvements in Dental Chip-Blowers, of which the following is a specification.

This invention relates to improvements in 10 dental appliances, and it pertains particularly to a chip blower in the form of a hand bulb provided with a stem and nozzle, whereby the chips resulting from drilling are blown from the tooth cavity. In the use 15 of such devices, there is great danger, from a sanitary view point, of disease germs being transmitted from one patient to another, due to the fact that the bulb when released will draw into the nozzle, particles of saliva 20 only to be later blown into the mouth of another person.

My invention comprises a double acting valve located in the stem between the nozzle and the bulb, whereby the air from the bulb 25 may be discharged through the nozzle, but the intake or supply means is located at a point outside of the mouth of the patient, thus preventing the bulb from drawing its supply of air through the nozzle. In this 30 manner I overcome the very serious objection above referred to, and I accomplish it by means of a simple valve construction, the details of which will be hereinafter specifically set forth.

35 The invention is more fully described in the following specification and clearly illustrated in the accompanying drawing, in which I have shown my device, in enlarged form, in central longitudinal section.

40 The numeral 1 designates a compressible bulb, preferably of rubber or like material; 2 designates the stem; 3 the nozzle, and 4 the valve casing. The bulb, stem and nozzle on the device shown are of ordinary construction, but instead of attaching the bulb to the one end of the stem, I interpose the 45 valve casing 4 with its valve arrangement which I will now describe. This casing 4 is provided at one end with a bead 5 over 50 which the contracted end of the bulb 6 fits. The other end of the casing is screw-thread-

ed internally to accommodate the externally screw-threaded end 7 of the stem 2, which stem is provided with a collar 18 adapted to bear against the end of the casing to 55 limit the movement of the stem when being inserted in the casing.

The inner wall of the casing 4 is tapered in opposite directions, to form two distinct valve seats 8 and 9 and a valve 10, which 60 serves as the outlet or exhaust valve, is normally seated against the seat 9. This valve is formed with a stem 11 which projects rearwardly, toward the bulb, and carries a nut 12 on its extremity. Between this nut 65 and the valve, is interposed a spring 13, which serves to keep the valve seated, as stated. Surrounding the valve stem 11 and fitting loosely over it, is a conical valve 14, adapted to serve as the intake valve, and to 70 seat against the opposite tapered seat, 8, in the casing. Radiating from this valve seat 8, are a plurality of openings 15 through the wall of the casing, which openings serve to supply air to the intake valve. 75

The operation is extremely simple: When the parts are assembled, and the bulb 1 is compressed, the air pressure will open the valve 10 against the tension of the spring 13, and permit the air, under pressure, to 80 pass through the stem and out of the nozzle. When the pressure on the bulb is released, the spring will immediately close the valve 10, thus preventing any intake through the nozzle, and, at the same time, the suction 85 caused by the expanding bulb will draw air through the openings 15, the conical valve 14 being free to unseat.

It is evident that with this device, nothing can be drawn into the bulb through the 90 nozzle, and that all the air to enter the bulb must pass through the intake valve, which, being located at a point remote from the nozzle, will not permit the entrance thereto of particles from the mouth of the 95 patient.

Having thus described my invention, what I claim and desire to secure by Letters Patent is:—

1. In a dental chip blower, the combination of a compressible bulb, a valve casing, 100 a hollow stem, a nozzle on the stem, a dou-

ble acting valve in the casing and means for keeping the exhaust or outlet valve opening normally closed.

2. In a dental chip blower, a compressible bulb, a hollow stem attached thereto, and a nozzle on the end of the stem, in combination with a valve casing located in the stem between the bulb and the nozzle, two

oppositely tapered valve seats in the casing, a valve adapted to normally close the outlet from said casing, a spring to keep said valve seated, and an intake valve adapted to be closed by pressure from the bulb when the outlet valve is opened. 10

In testimony whereof I affix my signature.

FREDERICK S. YODER.
